Images of Volvo Construction Equipment Autonomous Dumper Model HX01 Prototype, disclosed at Xploration Forum, Eskilstuna, Sweden, Sep. 12-16, 2016.

Primary Examiner — Mark A Goodwin

(74) Attorney, Agent, or Firm — Tucker Ellis LLP

(57) **CLAIM**

The ornamental design for an autonomous dumper, as shown and described.

DESCRIPTION

FIG. 1 is a front-left perspective view of an autonomous dumper showing our new design.

FIG. 2 is a rear-right perspective view thereof.

FIG. 3 is a front view thereof.

FIG. 4 is a rear view thereof.

FIG. 5 is a left side view thereof.

FIG. 6 is a right side view thereof; and,

FIG. 7 is a top view thereof.

1 Claim, 5 Drawing Sheets
